United States Patent Office

Des. 189,587
Patented Jan. 10, 1961

189,587

GLASS PANEL

Walter Lerch, 1 Uechtingstrasse, Gelsenkirchen-Schalke,
Germany

Filed Sept. 29, 1959, Ser. No. 57,732

Term of patent 14 years

(Cl. D36—11)

Fig. 1

Fig. 2

Fig. 3

Fig. 1 is a front elevational view of a glass panel showing my new design;

Fig. 2 is a rear elevational view;

Fig. 3 is a bottom-edge view on an enlarged scale; and
Fig. 4 is a sectional view on line 4—4 of Fig. 1 on the
same scale as Fig. 3.

I claim:

The ornamental design for a glass panel, as shown.
